APPARATUS FOR VENTILATING RAILROAD CARS

John D. Strobell, New Haven, Conn., assignor to
The Safety Car Heating and Lighting Company, Inc., a corporation of Delaware

Application March 12, 1941, Serial No. 382,868

2 Claims. (Cl. 98—6)

This invention relates to apparatus for ventilating a railroad car.

One of the objects of this invention is to provide ventilating apparatus which is simple, thoroughly practical, and durable in use. Another object is to provide apparatus of the above character, the manufacture of which will be economical both from the standpoint of labor and materials used. Another object is to provide apparatus of the above character in which the structural elements are so disposed as to attain a high degree of strength without heavy construction. Another object is to provide apparatus of the above character which may be easily and quickly installed on a car without extensive alteration thereof. A further object is to provide apparatus of the above character which operates effectively regardless of the direction of travel of the car. A still further object is to provide apparatus of the above character which introduces fresh air into the car while preventing or hindering the entrance of foreign particles therein. Other objects will be in part obvious and in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings in which is shown one of the various possible embodiments of the mechanical features of this invention,

Figure 1 is a diagrammatical top plan view of a railroad car having the ventilating apparatus installed therein;

Figure 2 is a diagrammatical side elevation of the car shown in Figure 1;

Figure 3 is an enlarged fragmentary vertical section taken on the line 3—3 of Figure 2;

Figure 4 is an enlarged horizontal section taken on the line 4—4 of Figure 2; and,

Figure 5 is a vertical section taken on the line 5—5 of Figure 4.

Similar reference characters refer to similar parts throughout the several views of the drawings.

As conducive to a clearer understanding of certain features of this invention, it might here be pointed out that the shipment of perishable and certain other commodities in freight cars often requires that the cars be ventilated. In the past, to provide ventilators in cars equipped with ice bunkers, the hatches in the car roofs have been

partially opened. This has not been satisfactory because foreign material, such as cinders, enters the car and also these hatches are seldom positioned so that practical and efficient air circulation is obtained within the car. Another system of ventilating freight cars has been to place ventilators in the ends of the cars. This has proved unsatisfactory because the air in the space between the ends of adjacent cars is in a state of turbulence, causing non-uniform pressure conditions which preclude a sufficient flow of air through the ventilator into or from the car. It is accordingly another object of this invention to provide ventilating apparatus for a railroad car or the like which overcomes the above-mentioned difficulties, as well as many others.

Referring now to the drawings in detail, and to Figures 1 and 2 in particular, a freight car, generally indicated at 10, has preferably four ventilators, generally indicated at 11, 12, 13 and 14, mounted on its side walls 15 and 16. As these ventilators are substantially similar in construction, detailed description will be limited to the construction of ventilator 14.

As best seen in Figures 2 and 3, ventilator 14 includes an intake or exhaust box generally indicated at 17 and a duct generally indicated at 18. Box 17 fits over an opening 20 (Figure 4) in the side wall 16 of the car and has a side wall 21 (Figures 3 and 4), top and bottom walls 22 and 23 (Figures 3 and 5), and an end wall 24 (Figures 4 and 5), the side opposite wall 24 being open to admit air. Connecting end wall 24 and side wall 21 is a corner 24a which is preferably curved for purposes to be disclosed more fully hereinafter. Flanges 25 extend outwardly from the top, bottom, and end walls of the box and provide means for connecting the box to the car side wall 16. The side of the box which faces the nearest end of the car is open, and bottom wall 23 slants downwardly toward this side (Figure 5). A door 26 is provided for closing the open side of the box, and it preferably is hingedly mounted thereon by a pin 27 and lugs 28. Suitable catches (not shown) are provided on car side wall 16 and on box 17 by means of which door 26 may be locked in an open or closed position.

The central and lower portions of duct 18 (Figure 3) are preferably rectangular in cross section, and its lower end is closed by a bottom wall 33 which slants outwardly and downwardly toward bottom wall 23 of box 17. The outside wall 31 of duct 18 preferably abuts against the inner side of car wall 16, the distance between duct side

walls 29 and 30 (Figure 4) being preferably substantially the same as the width of opening 20 in car wall 16. Duct side wall 31 (Figures 3 and 4) terminates at the top of opening 20, and flanges 32 are provided on duct side walls 29 and 30 and on its bottom wall 33 for connecting the bottom of the duct over opening 20. The flanges 25 and 32 of the box and duct may be connected to the car side wall in any suitable manner, such as by nuts and bolts 34 which extend through the flanges and car wall.

Duct 18 (Figure 3) extends upwardly from exhaust or intake box 17 in the insulated space 35 between the inner car wall 36 and the outside wall 16. Adjacent the top of the car above the top of any lading that may be placed therein when the car is in use, an elbow 18a is formed in the duct. This elbow extends through an opening 37 (Figure 3) in the inner wall 36 of the car and has a funnel-shaped mouth 38 which is preferably substantially greater in size than the cross-sectional area of duct 18 for reasons to be described hereinafter. A flange 39 is formed on the edge of mouth 38 for connecting the duct mouth to wall 36.

Referring now to Figures 4 and 5, a series of flat baffles 40 are vertically positioned within the lower portion of duct 18 and extend outwardly through opening 20 in car side wall 16. These baffles are preferably parallel to the open end of box 17, and each has a right angle flange 41 (Figure 4) formed on its inner edge which is secured to the inner wall of duct 18 in any suitable manner, such as by welding. The outer edges of the baffles are connected by a pair of spacers 42 and 43 which are preferably welded to the baffles and hold them in parallel relationship to each other. The baffles are of graduated widths, beginning with the baffle adjacent the open end of box 17 which extends only a slight distance into the box and increasing in width to the baffle at the other end of the series which extends a substantial distance into the box. As shown in Figure 5, box wall 23 slopes downwardly toward the end of the car, and the lower edges of baffles 40 are preferably spaced from wall 23 of box 17 to permit air to flow therebeneath and cinders to escape from the box, all as will be described more fully hereinafter. The upper edges of baffles 40 preferably lie in the same plane and are slightly spaced from box top 22.

Referring now to Figure 1, four ventilators of the type described hereinabove are positioned on car 10, two on opposite sides adjacent each end thereof. The intake or exhaust boxes are positioned in the lower portion of the car so that they may be reached from the ground, and to facilitate access to and operation of doors 26. The open side of each box faces that end of the car nearest thereto, and thus two boxes are always facing into the stream of air passing the car when it is in motion; the other pair faces away from this stream. When the car is in motion, the maximum air pressure available at the open sides of the boxes adjacent the leading end of the car is equivalent to the velocity pressure of air corresponding to the relative velocity between the car and the air. The pressure within the car is substantially that of the atmosphere so that the difference between the pressures at the open sides of the intake boxes and the internal pressure is available for causing air to flow into the car. When the car is standing still and a wind is blowing, an air stream enters the car in the same manner as when the car is moving. Thus, the

ventilators having openings facing the direction of movement of the car or toward a wind act as intake ventilators and direct a flow of air into the car. The stream of air passing the ventilators at the opposite end of the car creates a low pressure area within these ventilators and accordingly the ducts connected thereto, causing them to exhaust air from the interior of the car.

When a ventilator is directing air into the car, the baffles 40 in the ventilators change the direction of the air stream upwardly into duct 18, distributing it uniformly over the duct cross section. This is accomplished because each baffle extends a slightly greater distance into the intake box, and thus each baffle directs a portion of the air stream into the duct. By thus evenly changing the direction of the air stream, the baffles eliminate considerable turbulence within the lower portion of the ventilator, tend to render the pressures therein more uniform, and hence increase the quantity of air that can be handled.

Referring to Figure 4, the curved corner 24a connecting side and end walls 21 and 24 also aids in achieving this same effect in directing the air passing the innermost baffle around this corner into the duct. At the upper end of the intake ducts 18 the direction of the flow is again changed by the curved elbows, and because the mouths of these elbows are of substantially greater size than the cross-sectional area of the ducts, the air flows around the elbow, through the enlarged mouth 38, and into the car evenly and smoothly without turbulence and expands in diffusing rather than jet action.

Ventilators 17 also effectively prevent the entrance of cinders and other foreign material into the car. When cinders first enter an intake ventilator, they strike the baffles or the end of the intake box, follow to the inclined bottom 23 thereof, and roll out. If this does not stop the cinders, they are directed at right angles by the baffles against the inside wall of duct 18, and then to enter the car they must again turn at right angles, overcome the force of gravity, and travel up through the duct before they can enter the car. Thus, all foreign material must pass through a tortuous passage in the lower portion of the ventilator and then must overcome the force of gravity before it can enter the car. Foreign material thus stopped by the tortuous passage or the force of gravity falls to the bottom wall of duct 18 which because of its slant directs all foreign material outwardly onto the bottom wall of the intake box. This wall, because it slants toward the open side of the box and is spaced from the baffles, directs the foreign material out of the ventilator.

Thus, foreign material is effectively prevented from entering the car. Furthermore, the car is practically and efficiently ventilated by the apparatus disclosed hereinabove, which is operative regardless of the direction of travel of the car. Accordingly, thoroughly practical and efficient apparatus for ventilating a car has been provided which effectively and efficiently overcomes the difficulties mentioned hereinabove.

As many possible embodiments may be made of the above invention and as many changes might be made in the embodiment above set forth, it is to be understood that all matter hereinabove set forth, or shown in the accompanying drawings is to be interpreted as illustrative and not in a limiting sense.

I claim:

1. In a ventilator for delivering air to the in-

terior of a railroad car, in combination, an air intake box positioned in the lower portion of the side wall of said car and extending outwardly therefrom, said box having an opening facing the nearest end of said car, a duct leading upwardly from said box and opening into the interior of said car in the upper portions thereof, and a plurality of baffles positioned in said intake box and the lower portion of said duct and adapted to direct the flow of air upwardly into said duct from said box, said baffles being positioned substantially perpendicularly to the side wall of said car and extending into the stream of air entering said box when the car is in motion, whereby said baffles, said box and said duct form a tortuous passage to trap foreign material passing thereinto.

2. In a ventilator for delivering air to the interior of a railroad car, in combination, an air

intake box positioned in the lower portion of the side wall of said car and extending outwardly therefrom, said box having an opening facing the nearest end of said car, a duct leading upwardly from said box and opening into the interior of said car in the upper portions thereof, and a plurality of baffles positioned in said intake box and the lower portion of said duct and adapted to direct the flow of air upwardly into said duct from said box, the bottom of said duct slanting outwardly and downwardly into said intake box and the bottom of said intake box slanting downwardly toward the open end thereof, whereby said baffles, said box, and said duct form a tortuous passage to trap foreign material passing thereinto and said slanting bottom causes foreign material trapped by said passage to flow out of said ventilator.

JOHN D. STROBELL.
